AMPLIFIER OF HIGH-FREQUENCY ELECTRICAL CURRENTS.

Application filed June 7, 1923. Serial No. 644,034.

- Our invention relates generally to the amplification of high frequency electrical currents and is particularly adaptable to receiving radio signals.
- 5 A particular object of our invention is the reception and efficient amplification of very feeble high frequency currents such as those encountered in long distance radio communications.
- 10 A specific object of our invention is the efficient use of thermionic vacuum tube amplifiers in tandem without producing oscillations in the circuits of such amplifiers thereby preserving rather than destroying their functions. A further object is the combination of ordinary amplification obtained from a vacuum tube with that form of amplification generally known as amplification by regeneration.
- 15 Great difficulty is had in endeavoring to use a number of vacuum tubes as amplifiers of high frequency electrical currents in tandem to secure a high order of amplification on account of the reactive effects of the 20 circuits of the various tubes on each other, which reactive effects tend to set up oscillations, particularly in the input circuit of the first tube. If such oscillations are set up they will be amplified by the subsequent 25 tubes, and if there are sufficient stages of amplification there will usually result a paralyzing of the action of the last tubes and no signals will be heard. This tendency to oscillate exists even where there is no 30 reactive or feed-back arrangement deliberately included somewhere in the system, and the control of this tendency naturally becomes much more difficult if a feed-back arrangement is deliberately included in the 35 system.
- 40 Our invention will be best understood by reference to the accompanying drawing in which the figure illustrates our invention employed in a system in connection with the reception of radio signals. It includes the combination of a straight radio frequency amplifier reenforced by an amplifier having regenerative action as an example of an arrangement for employing 45 vacuum tubes in tandem for highly efficient selective high frequency current amplification, and including the provisions of our invention for maintaining efficiency while preventing oscillation production.
- 50 A is an antenna grounded at G including in circuit therewith the tuning elements inductance L_1 and variable capacity C_1 . The antenna is coupled through inductance L_1 to the secondary circuit containing inductance L_2 and variable capacity C_2 . VT_1 55 is a three electrode vacuum tube including the secondary circuit in its input circuit and having a tunable circuit composed of inductance L_3 and variable capacity C_3 tightly coupled to its output circuit, as indicated by the full auto transformer or direct coupling across coil L_3 . The inherent grid-to-plate capacity, indicated by capacity C_T in dotted lines, links the input circuit to the output circuit. Battery B_1 provides for heating 60 the filament of this vacuum tube, the amount of heating being controllable through variable resistance R_1 . The connection of the input circuit to the negative side of the filament provides for biasing the grid of this tube to cause it to operate effectively as a straight amplifier. Battery B_2 supplies energy to the output circuit of the 65 amplifier tube.
- 70 Vacuum tube VT_2 has the tunable circuit containing inductance L_3 and variable capacity C_3 included in its input circuit and, as indicated by the illustrated tight coupling, is efficiently linked to the amplifying or output circuit of tube VT_1 . The output 75 circuit includes inductance L_4 variably coupled to inductance L_3 for a regenerative action; that is, increase of amplification in tube VT_2 , and which is selective increase of amplification by reason of the feed-back 80 coupling to selective circuit L_3C_3 . Resistance R in parallel relation with capacity C_4 provides the commonly known grid leak-stopping condenser combination. Battery 85 B_3 provides for heating the filament of this second tube, the extent of heating being controllable through resistance R_2 . The connection of the input circuit to the positive side of the filament provides for operating this tube as a detector, this in addition to 90 its operation as an amplifier through regeneration. Battery B_4 provides a source of energy supply for the output circuit of this second tube. Telephones T provide for detecting the signals aurally. The condenser 95 C_5 provides a by-pass for the high frequency electrical currents around the high impedance of the telephones.
- 100 We have found that by including in the output circuit of the first vacuum tube a 105

choking device D properly proportioned in its reactive effects for the high frequency electrical currents contemplated for selective amplification in the illustrated system stable operation of the circuit arrangement herein described is obtained, and that this is also possible even when employing a regenerative action to such a degree that high order of amplification is secured. Without this device in the system illustrated when operated at the high frequencies and amplifications contemplated, or its equivalent in effect, it is in practice impossible to use any amount of regeneration without setting the system into oscillations and destroying its function as a receiver.

An example of a simple and readily available reactive device we have found to give excellent results at the high frequencies of broadcasting with which we have experimented is a single ear piece of the pair of ear pieces of an ordinary head telephone set having a direct current resistance of about 2,000 ohms. It includes a winding of many turns of very fine wire on an open iron core, and offers high impedance to currents of the high frequency order we have referred to; that is, sufficiently high to be of the same order of magnitude as the internal output impedance of the type of tube we used in position VT₁ under the conditions it was operated. The construction of this device inherently compels its impedance for the high frequencies referred to to be capacitive in nature, the effective high frequency path through the device being the distributed capacity path indicated by the capacity C_D in dotted lines, this being because such telephones are used in connection with the low frequencies of voice frequency currents, and though made to be resonant at a frequency above the practical range of voice frequencies to avoid distortion, yet this resonance is not too far removed therefrom in order to preserve a practical degree of efficiency. This resonant point will in general be well below 100,000 cycles, and never reaches frequencies sufficiently high for the small inherent tube capacity to become a sufficient coupling for regenerative oscillation difficulties. In accordance with a well known principle all electrical devices react capacitively for frequencies above the natural period of the device. The conductive path provided by the coil admirably adapts the device for the use made of it, as it permits of energizing the plate of tube VT₁ from battery B₂, and thus avoids use of other apparatus and circuits for this purpose.

That the system functions to produce the results set forth under the conditions outlined and illustrated is readily appreciated by analyzing the actions and reactions that inherently exist therein with the aid of com-

mon knowledge as to some of the practical effects of them. Assume circuit L₂C₂ set to a given frequency. It will selectively absorb from the antenna current energy of the set frequency and favorably offer it to tube VT₁ for amplification with the natural amplifying ability of the tube as energized, with the result that amplified current of the selected frequency will predominate in the output circuit. Now if effort be made to adjust circuit L₃C₃ to this same frequency to selectively pass some of the amplified energy on to tube VT₂ for further amplification, the practical matter of varying the electrical constants in carrying out this effort will inevitably result in transiently producing in the output circuit of VT₁ the variety of reactions to the set frequency of which circuit L₃C₃ is capable, and, as is well known, the reactions will be capacitive when the natural period of the circuit is below the set frequency, inductive when above, and highly resistive but non-reactive when in tune or accord, and at which setting the maximum energy due to the natural amplifying ability of the tube would be delivered to tube VT₂ if inherent tube capacity C_T did not exist. The magnitude of these reactions will depend upon the degree of coupling, being the stronger the tighter the coupling, and contemplated as tight in our system as indicated by the very tight coupling of the full auto transformer.

Using the knowledge that the grid-to-plate capacity of commercial tubes suffices as an effective coupling between the input and output circuits at high frequencies to feed-back enough energy to greatly alter the natural amplification of the tube, and can artificially increase amplification to even produce oscillations, and that the fed back energy is of proper phase for this when the reaction of the output circuit is inductive to the set frequency, rather than non-reactive but resistive, as it is when circuit L₃C₃ is resonant and best adjusted to transfer the set frequency, it is realized that circuit L₃C₃, in the position shown, performs the two functions of selectively controlling amplification and selectively controlling energy transfer, maximum results from which are not had at the same adjustment. If the coupling is so tight that oscillations are produced at the adjustment for maximum amplification then the system cannot be operated at this adjustment. As a practical matter a variable receiver cannot be operated at the adjustment for resonant energy transfer for the reason that the oscillating adjustment would inevitably be encountered in attempting to change tune from any one frequency to another.

If the coupling be loosened to reduce the reaction on the output circuit sufficiently to prevent oscillations the energy available for

transfer may still be large but the efficiency of transfer has been sacrificed. Consequently overall efficiency requires that the coupling not be the control means, and we 5 satisfy the requirement by maintaining a coupling such that oscillation will be produced by its unmodified reaction, and providing means independent of coupling for preventing the coupling reaction from being 10 effective as an oscillation cause, but fully effective for energy transfer. The importance of this is readily apparent from practical considerations. Assume it is desired to have tube VT_1 amplify the maximum 15 amount below oscillation production and transfer the energy with a 50% coupling to a second tube, but it is found that without our system the coupling must be reduced to 25% before oscillations can be 20 stopped. It is obvious that our system will transfer double the energy which, when applied to the detector, takes advantage of the "square law" of detection to give an overall 25 result four times as good as the system that cannot use tight coupling. With a given 30 coupling oscillation can be prevented by decreasing the natural amplifying ability of the tube through decreasing the energizing potentials, as by introducing energy consuming devices into the system. Such methods are undesirable for many reasons, and it will be noted that our system secures the desired result while avoiding both procedures. 35 Considering the inclusion in the system of regeneration in tube VT_2 , it is apparent that if the magnitude of the current in circuit L_3C_3 is increased by additional amplification in this manner the effective reaction of this 40 circuit on the output circuit of tube VT_1 is increased, so that if dependence were had on looseness of coupling to prevent oscillation it would be necessary to further loosen the coupling in proportion to the amount of 45 regeneration used in order to keep VT_1 from oscillating. The fact that a high order of regeneration in VT_2 can be used in company with tight coupling is practical proof of the effectiveness of our means for preventing 50 oscillations.

The device being effective in keeping back oscillations in the combination such as we have illustrated, it is naturally sufficient for a combination not involving a deliberate regenerative action but having merely accidental or constructional reactions between the various stages of amplification or reactions of plate circuits through the internal capacities of the vacuum tubes. 55

Having described our invention, we claim:

1. In a system for efficiently amplifying high frequency electrical currents the combination of a three electrode vacuum tube amplifier having inherent capacity between its electrodes, means for energizing said 60 tube to operate as an efficient amplifier, a high frequency tunable circuit connected to the input electrodes of said amplifier, a second three electrode vacuum tube having a turnable circuit in its input circuit adapted to be varied in consonance with said first tunable circuit, said second circuit being so closely coupled with the output circuit of said first tube to efficiently transfer energy therefrom that its transient reactions on said output circuit in the operation of varying it to follow said first tunable circuit inevitably include that reaction which unmodifiedly acting through said inherent tube capacity is of such phase and potential as to cooperate 70 with said first tunable circuit to produce oscillation by regenerative action, and means permitting maintaining said close coupling between said circuits and said efficient amplification of said tube while preventing said oscillation including impedance means associated with a circuit of said first tube for modifying the effect through said inherent capacity of said coupling reaction to sufficient degree that said second circuit 75 may be varied at will unaccompanied by oscillation production. 80
2. In a system for selectively and efficiently amplifying high frequency electrical currents the combination of a three electrode vacuum tube amplifier, a high frequency tunable circuit connected to the input electrodes of said tube, a second three electrode vacuum tube having a tunable circuit in its input circuit adapted to be varied in consonance with said first tunable circuit, said second circuit being closely coupled with the output circuit of said first tube to efficiently transfer energy therefrom, and an impedance element connected in said output 90 circuit having impedance to high frequency currents for which the system is designed of the order of the internal output impedance of said first tube. 95
3. In a system for efficiently amplifying high frequency electrical currents the combination of a three electrode vacuum tube amplifier having inherent capacity between its electrodes, direct current means for energizing plate and filament electrodes of said tube to operate as an efficient amplifier, a high frequency tunable circuit connected to the input electrodes of said tube, a second three electrode vacuum tube having a tunable circuit in its input circuit adapted to be varied in consonance with said first tunable circuit, said second circuit being so closely coupled with the output circuit of said first tube for efficiently transferring energy therefrom that its transient reactions on said output circuit in the operation of varying it to follow said first tunable circuit inevitably include that reaction which unmodifiedly acting through said inherent tube capacity is of such phase and potential as to cooperate 100 with said first tunable circuit to produce oscillation by regenerative action, and means permitting maintaining said close coupling between said circuits and said efficient amplification of said tube while preventing said oscillation including impedance means associated with a circuit of said first tube for modifying the effect through said inherent capacity of said coupling reaction to sufficient degree that said second circuit 105 may be varied at will unaccompanied by oscillation production. 110

- with said first tunable circuit to produce oscillations by regenerative action, and means permitting maintaining said close coupling between said circuits and said efficient amplification of said tube while preventing said oscillations including conductive impedance means associated with a circuit of said first tube for modifying the effect through said inherent capacity of said coupling reaction to sufficient degree that said second circuit may be varied at will unaccompanied by oscillation production and the tube electrode in said circuit may be energized by a direct current potential.
15. 4. In a system for efficiently amplifying high frequency electrical currents the combination of a three electrode vacuum tube amplifier having inherent capacity between its electrodes, a tunable high frequency circuit connected to the input electrodes of said tube, connections for operating said tube as an efficient amplifier, a second three electrode vacuum tube having a tunable circuit in its input circuit adapted to be varied in consonance with said first tunable circuit, said second circuit being so closely coupled with the output circuit of said first tube to efficiently transfer energy therefrom that its transient reactions on said output circuit in the operation of varying it to follow said first tunable circuit inevitably include that reaction which unmodifiedly acting through said inherent tube capacity is of such phase and potential as to cooperate with said first tunable circuit to produce oscillation by regenerative action, means for overcoming a desired degree of said regenerative action while permitting maintaining said efficient amplification and said close coupling between said circuits whereby said second circuit may be varied at will unaccompanied by oscillation production, and means for operating said second tube as a stable amplifier of the currents delivered thereto.
45. 5. In a system for efficiently amplifying high frequency electrical currents means for the multiple amplification of said currents including the combination of a three electrode vacuum tube amplifier having inherent capacity between its electrodes, a high frequency tunable circuit connected to the input electrodes of said tube, a second three electrode vacuum tube having a tunable circuit in its input circuit adapted to be varied in consonance with said first tunable circuit, said second circuit being so closely coupled with the output circuit of said first tube to efficiently transfer energy therefrom that its transient reactions on said output circuit in the operation of varying it to follow said first tunable circuit inevitably include that reaction which unmodifiedly acting through said inherent tube capacity is of such phase and potential as to cooperate with said first tunable circuit to produce oscillations by regenerative action, means for returning amplified energy from the output circuit of said second tube to said second tunable circuit in degree sufficient to cause said second tube to selectively increase its amplifying ability without generating oscillations, but resulting in an intensified reaction of said second tunable circuit on the output circuit of said first tube, and means for preventing said first tube from generating oscillations while maintaining said close coupling in the presence of said regenerative action in said second tube, whereby both tubes function as efficient and stable amplifiers of the same selected high frequency current.
20. 6. In a system for efficiently amplifying high frequency electrical currents means for the multiple amplification of a selected frequency current including a pair of three electrode vacuum tube amplifiers, a selective circuit connected to the input electrodes of one of said tubes, couplings linking the output circuits of both of said tubes to said selective circuit whereby it performs the dual function of simultaneously selectively increasing the amplifying ability of both of said tubes, and means associated with both of said tubes for limiting the degree of said selective increase of amplifying ability whereby both of said tubes function as stable amplifiers.
25. 7. In an amplifier of high frequency electrical currents the combination of a three electrode vacuum amplifier having inherent capacity between its electrodes, a tunable circuit in the input circuit of said amplifier, a second three electrode vacuum tube having a tunable circuit in its input circuit adapted to be varied in consonance with said first tunable circuit, said second circuit being so reactively associated with the output circuit of said first tube to efficiently transfer energy therefrom that its transient reactions on said output circuit in the operation of varying it to follow said first tunable circuit inevitably include that reaction of inductive nature which unmodifiedly acting through said inherent tube capacity produces oscillation by regenerative action, and a capacitively reacting element associated with said output circuit to alter the overall reaction thereof to sufficient degree to prevent said oscillation production while maintaining said coupling relation between said circuits, whereby the tuning of said second circuit may be varied at will unaccompanied by oscillation production.
30. 8. In an amplifier of high frequency electrical currents the combination of a three electrode vacuum tube amplifier having inherent capacity between its electrodes, a tunable circuit in the input circuit of said amplifier, a second three electrode vacuum tube having a tunable circuit in its input

- circuit adapted to be varied in consonance with said first tunable circuit, said second circuit being so reactively associated with the output circuit of said first tube to efficiently transfer energy therefrom that its transient reactions on said output circuit inevitably include that reaction of inductive nature which unmodifiedly acting through said inherent tube capacity produces oscillation by regenerative action, and means for preventing said oscillation production while maintaining said efficient coupling comprising a coil in said output circuit so wound that its reaction to all the current frequencies adapted to be selected by said tunable circuits is inevitably capacitive, and is sufficient to oppose said inductive reaction to adequate degree to modify the overall output circuit reaction by that amount necessary to prevent oscillation production, whereby the tuning of said second circuit may be varied at will unaccompanied by oscillations.
9. In an amplifier of high frequency electrical currents the combination of a three electrode vacuum tube amplifier having inherent capacity between its electrodes, a tunable circuit in the input circuit of said amplifier, a second three electrode vacuum tube having a tunable circuit in its input circuit adapted to be varied in consonance with said first tunable circuit, said second circuit being so reactively associated with the output circuit of said first tube to efficiently transfer energy therefrom that its transient reactions on said output circuit inevitably include that reaction of inductive nature which unmodifiedly acting through said inherent tube capacity produces oscillation by regenerative action, and means for preventing said oscillation production while maintaining said efficient coupling comprising a reactance element so connected in said output circuit as not to prevent the flow of direct current therein but presenting a reaction to all the current frequencies adapted to be selected by said tunable circuits that is sufficiently capacitive to oppose said inductive reaction to adequate degree to modify the overall output circuit reaction by that amount necessary to prevent oscillation production, whereby the tuning of said second circuit may be varied at will unaccompanied by oscillations.
